United States Patent Office.

JOHN MARTINO, OF PHILADELPHIA, PENNSYLVANIA.

Letters Patent No. 99,580, dated February 8, 1870.

FENDER FOR FIRE-PLACE STOVE.

The Schedule referred to in these Letters Patent and making part of the same.

To all whom it may concern:

Be it known that I, JOHN MARTINO, of the city and county of Philadelphia, in the State of Pennsylvania, have invented a new and useful Improvement in Fenders for Fire-Place Stoves; and I do hereby declare that the following is a full, clear, and exact description thereof, reference being had to the accompanying drawings, making part of this specification, in which—

Figure 1 is a front elevation of the fender.

Figure 2 is a horizontal section through the fender.

Figure 3 is a horizontal section, showing the sliding door moved to one side of the central passage through the fender.

Figure 4 is a cross-section through the fender.

Similar letters of reference indicate corresponding parts in the several figures.

The object of this invention is to so construct a fender, having a continuous guard-rail, and an opening through it beneath such rail, that the ash-pan or ash-drawer, as the case may be, can be conveniently removed from the ash-chamber of a fire-place stove, through said opening, without moving the fender, or any part of the guard-rail thereof, as will be herein-after explained.

I am aware that, previous to my invention, it has been suggested to hinge the guard-rails of fenders for fire-place stoves, so that by swinging around the hinged sections, the ash-drawers could be readily removed from or replaced in their chambers, and I do not claim such contrivances as my invention.

The following description of my invention will enable others skilled in the art to understand it.

In the accompanying drawings—

A represents the base of the fender, which is adapted to fit snugly to the front wall of the base section of a fire-place stove.

On this base are constructed two ornamental side sections C C, forming two-thirds, more or less, of the length of the fender, on which section the guard-rail B is constructed, or permanently secured. This guard-

rail is continuous, that is to say, it extends from one end of the fender to the other, and consequently, extends across or bridges the space between the ornamental sections C C, as shown in fig. 1.

The rail B may be ornamented in any desired manner, and into that portion of its bottom edge which projects from the sections C C, a groove, a, is made, which is continued over the space between the sections. Directly beneath groove a, a corresponding groove, a', is made into the projecting lip of the fender-base A.

These grooves receive, keep in place, and afford guides for a movable section, D, which is of such length as will close the central opening through the fender, when this section is adjusted as shown in figs. 1 and 2.

The movable or sliding section D may be ornamented with open-work, in harmony with the side, or stationary sections C C, and, at its ends, or in its centre, a handle or lug may be formed, to afford convenient hold, when it is desired to slide the section D to one side of the opening.

A fender, thus constructed, need occupy very little space in front of a stove, and need not be taken from its place when it is desired to remove the ash-drawer, as this draw can be conveniently removed through the space between the sections C C, and beneath the guard-rail.

It is obvious that the guard-rail, and the filling between this rail and the fender-base, may be ornamented according to any design which fancy may suggest.

Having described my invention,

What I claim as new, and desire to secure by Letters Patent, is—

A fender, which is constructed with a continuous guard-rail, beneath which is an opening provided with a sliding section or door, substantially as described.

JOHN MARTINO.
